HYDRAULIC JACK RESERVOIR

Frank J. Jakoubek, Elmwood Park, Ill., assignor to Star Jack Company, Inc., River Grove, Ill., a corporation of Illinois

Application November 19, 1953, Serial No. 393,144

11 Claims. (Cl. 137—587)

The invention relates generally to improvements in hydraulic jacks, but relates more particularly to means for baffling the oil returning to the oil reservoir in hydraulic jacks of the type requiring vent openings. In jacks of this type, oil returning to the reservoir on release of the load, returns under high pressure. Since in elevating the ram a large part of the oil in the reservoir has been withdrawn, the oil reservoir space is largely filled with atmospheric air. Hence, on the return of the oil to the reservoir, the air in the reservoir must be displaced and discharged through the vent opening. On the release of the oil pressure when returning to the reservoir, difficulty has been encountered, in that part of the oil would become admixed with the air, forming an aerosol, part of which would spray out through the vent or relief opening.

The object of the present invention is to provide means which will prevent the atomization of the oil on its return to the oil reservoir and its passage out the vent opening.

Another object of the invention is to provide simple, inexpensive and efficient means for baffling the oil on its return to the oil reservoir.

A still further object of the invention is to provide baffle means which may be readily assembled with the remaining parts of the jack and which, when assembled, will automatically maintain the position in which it is placed without the necessity of extraneous fastening means.

The above mentioned objects of the invention, as well as others, along with the advantages thereof, will more fully appear as the specification proceeds.

In the drawings:

Fig. 1 is a vertical sectional view through a jack embodying the invention.

Fig. 2 is a transverse sectional view on the line 2—2 of Fig. 1, viewed in the direction of the arrows.

Fig. 3 is a fragmentary detail view on the line 3—3 of Fig. 1, viewed in the direction of the arrows, and

Figs. 4 and 5 are fragmentary sectional views showing modified forms of the invention.

In the drawings 10 represents the base of the jack, in which the various valve mechanisms are located. There is no particular novelty in the valve mechanisms and in the pump, so that they have been illustrated in rather schematic form and will be described only briefly.

An oil reservoir tube 11 is fitted at 12 to the pump base, the upper end being closed by a cap 13. An inside cylinder 14 is provided, one end of which is threaded into the base at 15 and into the cap 13 at 16. Within the cylinder 14 is a ram member 17 which projects through the cap 13, being suitably sealed against oil leakage by means of the O ring 19. At the lower end, the ram carries a ram cup support washer 20 and a ram cup 21.

In the base of the jack there is provided a pump piston 22 which is shown in its inner position and which, by means of a lever 23, may be reciprocated in order to force oil under pressure into the cylinder 14 under the

2

ram cup 21, thereby to force the ram upwardly. The piston is actuated by means of the lever 23.

24 as a whole represents the intake valve assembly, which comprises balls 25 and 26 that are pressed against seats 27 and 28 respectively by springs 29 and 30 respectively, the whole assembly being held in place by the screw plug 31. 32 as a whole represents a release valve assembly which includes a ball 33 pressed against a seat 34 by means of a spring 35, the assembly being held in place by the screw plug 36. A plunger 37 is slidably mounted in the sleeve 38. The plunger 37 may be moved inwardly to press the ball away from its seat by means of the lever 39 which is pivoted at 40 on a bracket 41 carried by the base of the jack.

The space between the cylinders 11 and 14 provides a reservoir for the hydraulic fluid which, when the ram is in its lowermost position, is at a level just below the filler screw plug 42. At a level above the filler plug 42 there is provided a vent plug 43. The plug 43 remains in position at all times, but is cut away or flattened on one side at 44 to provide a vent opening to atmosphere.

In the oil reservoir space there is provided an oil baffle 45, which as illustrated, takes the form of a spiral spring, the lower convolution 46 being of a diameter approximating the inside diameter of the outer tube 11 and finding its support upon the upper part of the base 10. The upper convolution 47 is of a size slightly less than that of the external diameter of the cylinder 14 so as snugly to grip the surface of the tube 14. Thus when the baffle member 45 is placed in position a slight frictional gripping action of the upper convolution on the outer surface of the cylinder 14 serves to hold the baffle in position against the action of oil movement, when discharging back into the reservoir upon the release of the release valve. The baffle 45^x (Fig. 4) is like baffle 45 except that it is inverted and resiliently engages the walls of both the inner and outer tubular members. The Fig. 5 baffle, 45^y, is in the form of an inverted V resting on the base and resiliently engaging walls of both the inner and outer tubular members.

Operation of the jack

It will be understood that as the piston 22 moves from its inner position to its outer position under the action of the lever 23, the suction will move the ball 25 away from its seat, thus causing oil to flow through the conduit 48 into the bore 49 and thence by conduit 50 into the space 51 at the end of the piston 22. When the piston is moved in the direction of the arrow indicated in Fig. 1, the oil previously withdrawn from the reservoir will be forced under pressure back through the conduit 50 and thence by means of conduits 52 and 53 into the space under the member 21 of the hydraulic ram 17, thereby forcing the ram away from the base. It will, of course, be understood that the pressure stroke of the piston 22 will move ball 26 away from its seat, thereby communicating conduits 50, 52 and 53. Reciprocatory action of the pump piston will be continued until the ram has been elevated or projected the desired extent. Of course, as oil flows into the space under the ram, the level of oil in the reservoir will drop until when the ram has reached its maximum outward extent, at which time there will be very little oil remaining in the reservoir. Obviously as the oil level drops in the reservoir atmospheric air will flow through the vent opening 44 into the reservoir space until the external and internal air pressures are equalized. Since considerable pressure is required to raise the ram, it will be understood that the oil which is locked in place under the ram will be under high pressure.

In order to permit the ram to return to its lower position it is necessary to operate the release valve 32. This is done by causing the lever 39 to swing in the direction

of the arrow which then moves the plunger 37 inwardly, thereby removing the ball from its seat 34, whereupon the oil under high pressure flows back through the conduit 53, past the seat 34 into the conduit 54 in the plunger 37 and thence back into the reservoir by means of the conduit 55. Since the oil discharging from the top of the conduit 55 is under high pressure and is discharging into the reservoir space which contains a considerable amount of air under atmospheric pressure, the rapid expansion of the oil tends to form a mist or aerosol, a part of which would pass out through the vent opening 44 unless restrained. With the present construction, however, the oil spray discharging from the conduit 55 encounters a series of convolutions of the baffle 45, 45^x or 45^y, as the case may be, which baffle acts effectively to disperse the oil and prevent the formation of an aerosol admixture. In this way the oil is enabled to flow back into the reservoir space, displacing the air as the oil level rises and causing the displaced air to flow quietly out through the opening 44 without, at the same time, causing any substantial amount of oil spray or vapor to be discharged from the reservoir.

While the invention is extremely simple, it has been found effective to overcome the objectionable aerosol spray discharge action heretofore found in hydraulic jacks of this type. The baffle is also low in cost and can be assembled quickly and easily.

I claim:

1. Means for preventing the discharge of hydraulic fluid through the air vent opening leading to external atmosphere from one end of the annular hydraulic jack reservoir space formed between spaced inner and outer tubular members as a result of hydraulic fluid charging into said annular space under pressure through an opening located at the end opposite said air vent, said means comprising a plurality of convolutions of different sizes positioned in the space between the outer wall of the inner tubular member and the inner wall of the outer tubular member, and between the air vent and the hydraulic fluid opening.

2. The combination set forth in claim 1 in which one of the convolutions of the baffle means frictionally engages, at least in part, a wall surface of one of said tubular members for holding the baffle means against movement in at least one direction.

3. The combination set forth in claim 1 in which one of the convolutions of the baffle means is seated, at least in part, upon a fixed part of the jack reservoir.

4. The combination set forth in claim 1 in which one of the convolutions of the baffle means is seated, at least in part, upon the base portion of the jack reservoir.

5. Means for preventing the discharge of hydraulic

fluid through the air vent opening leading to external atmosphere from one end of the annular hydraulic jack reservoir space formed between spaced inner and outer tubular members as a result of hydraulic fluid charging into said annular space under pressure through an opening located at the end opposite said air vent, said means comprising a tapering coil in the space between the outer wall of the inner tubular member and the inner wall of the outer tubular member, and between the air vent and the hydraulic fluid opening.

6. The combination set forth in claim 5 in which the coil is a spring coil and in which one of the convolutions thereof resiliently engages, at least in part, one of the wall surfaces of the inner or outer tubular members.

7. The combination set forth in claim 5 in which the coil is a spring coil and in which a plurality of convolutions thereof resiliently engage, at least in part, portions of the walls of the inner and outer tubular members.

8. The combination set forth in claim 5 in which a part of the coil member is seated upon a fixed part of the jack reservoir structure.

9. Means for preventing the discharge of hydraulic fluid through the air vent opening leading to external atmosphere from one end of the annular hydraulic jack reservoir spaced formed between spaced inner and outer tubular members as a result of hydraulic fluid charging into said annular space under pressure through an opening located at the end opposite said air vent, said means comprising a tapering spiral coil member in the space between the outer wall of the inner tubular member and the inner wall of the outer tubular member and between the air vent and the hydraulic fluid opening, one end being seated upon the base portion of the jack reservoir, and the other end frictionally engaging, at least in part, a wall portion of one of said tubular members.

10. The combination set forth in claim 9 wherein the largest dimension of the coil is seated upon a fixed part of the jack reservoir.

11. The combination set forth in claim 9 in which the coil is a spring coil wherein the largest dimension is seated upon a fixed part of the jack reservoir and the smallest dimension resiliently embraces, at least in part, the outer surface of the smaller tubular member.
